AUXILIARY GRATE FOR STAGE ICING

Horace Giddings, San Francisco, Calif.

Application October 17, 1934, Serial No. 748,600

17 Claims.

(Cl. 62—19)

The present invention relates to a movable or swinging auxiliary grate for permitting the partial icing of a refrigerator car.

In the use of refrigerator cars, it is frequently desirable or expedient to only partially fill the ice compartments with ice, instead of completely filling them according to the more usual practice. This partial icing is known in the art as stage icing. When such partial or stage icing is resorted to, it is considered more efficient, for reasons which need not be herein described, to fill the upper portion of the ice compartment rather than the lower portion, and, in order to accomplish this, some kind of a temporary removable grate is installed in the ice compartment, at such a distance above the regular or bottom grate as will support the desired quantity of ice in the upper portion of the ice compartment.

The objects of the present invention are to provide an auxiliary grate, built into the ice compartment, which can be quickly moved into position to support a partial load of ice for stage icing, and which, when not so positioned and used, can be folded into the inner walls of the ice compartment in such a manner as to not interfere either with the full icing of said compartment or with the free circulation of air around and through the walls of said compartment. By providing the auxiliary grate as a built-in feature of the ice compartment, it is always instantly available for use, without requiring additional parts or materials; and by folding it into the walls of the ice compartment when not in use, it does not interfere in any way with the full or normal icing of the car. Furthermore, the particular construction herein described permits the auxiliary grate to be moved to either operative or inoperative positions with the least possible expenditure of labor and time.

Other objects and advantages of the invention will become apparent from the following description of a preferred form thereof, which should be read with the understanding that the form, construction and arrangement of the various parts may be changed within the limits of the claims hereto appended without departing from the spirit of the invention as defined therein.

Reference will be made to the accompanying drawings in which

Fig. 1 is a transverse section through the ice compartment of a refrigerator car, showing my auxiliary grate in inoperative or folded position.

Fig. 2 is a horizontal section on the line 2—2 of Fig. 1.

Fig. 3 is a transverse section similar to Fig. 1 showing the grate in operative position.

Fig. 4 is a horizontal section on the line 4—4 of Fig. 3.

Fig. 5 is a vertical section on the line 5—5 of Fig. 1.

Fig. 6 is a vertical section on the line 6—6 of Fig. 3.

Fig. 7 is a sectional detail, enlarged, of the grate in operative position.

In the drawings, the reference numerals 8 and 9 designate respectively the walls of the sides and ends of a refrigerator car, the detailed construction thereof as to framing, sheathing, insulation, etc., being omitted. 10 is the bulkhead separating the ice compartment from the lading compartment of the car. 11 is the lining or inner wall of the ice compartment, which may be formed in any customary way, and is herein shown, by way of example, as a screen. 12 is the usual or permanent grate in the lower portion of the ice compartment upon which the ice rests in full or normal icing. So much is the usual construction of a refrigerator car.

The present invention contemplates an auxiliary grate preferably formed of a plurality of sections as, for example, three sections numbered 13 and 13', the two sections 13 being at the sides of the ice compartment, and the section 13' being in the middle between them. When raised to operative position, the sections 13 and 13' form a continuous horizontal grate across the entire area of the ice compartment at a suitable level between its top and bottom, as shown in Figs. 3 and 4.

The grate sections 13 and 13' are mounted to swing downwardly into inoperative position, as shown in Figs. 1, 2 and 5. The end sections 13 swing downwardly against the side walls 8 of the car, and the center section 13' swings against the end wall 9. The ice compartment lining 11 is cut away, as shown at 14 and 14', where the grate sections swing down, to allow the latter to hang vertically against the walls of the car, so that their inner surfaces are flush with the lining 11, and form a continuation thereof.

The grate sections 13 and 13' are preferably formed of sheet metal stamped with troughs or corrugations 15 which provide both strength and free drainage, the troughs having holes 15' in their sides. The troughs 15 are so arranged as to be vertical when the grate hangs in folded position, as shown in Figs. 1, 2 and 5. It will be noted, particularly from Fig. 2, that the corrugated construction of the grate sections presents the least possible obstruction to the vertical move-

ment of air through the spaces 8' and 9' between the ice compartment lining 11 and the car walls.

The grate sections 13 and 13' are mounted in hinged brackets 16, the brackets for the side sections 13 being secured to the side walls 8 of the car and the brackets for the center section 13' being secured to the end wall 9. The brackets 16 are all similar, as best shown in Fig. 7, having a triangular web 17 extending outwardly from the wall of the car and provided with an inclined upper edge. These webs 17 are provided with irregular apertures 18, through which the hinge pin 19 of the grate extends. The opposite or free edge of each grate section is provided with a downwardly turned flange 20 formed to hook over and rest upon an upwardly flanged support. In the case of the center section 13', this support is a flanged bracket 21 secured to the framing of the bulkhead 10, as shown in Fig. 7, and in the case of the side sections 13' their free edge flanges are adapted to engage and rest upon upturned side flanges 22 on the center section 13', as shown in Figs. 3 and 4.

The elongated hinge apertures 18 are provided to permit the grate sections to clear their supporting flanges 21 and 22 when being swung to and from horizontal position. For example, when the section 13', shown in Fig. 7, is to be lowered to its vertical or inoperative position, as illustrated in dotted lines, its left hand end is first raised and then the entire section is shifted horizontally toward the right, the hinge pin 19 riding rearwardly in the slot 18 to enable the flange 20 to clear the bracket 21. The section is then lowered to its vertical position against the wall 9 of the car, in which position the hinge pin 19 rests in a notch 23 formed in the bottom of the slot 18 and is thereby prevented from sliding in and out. The lower or free edge of the grate section is prevented from swinging out into the ice compartment by any suitably formed latch, as for example, a lug 24 pivotally mounted at 25, Figs. 3 and 6.

In swinging the auxiliary grate from inoperative to operative position, a man descends into the ice compartment, lifts up the center section 13' and one of the side sections 13, then climbs up on the partial grate so formed and pulls up the other side section after him. Loops or bails 50 26 are provided in one of the side sections to facilitate pulling it up from above by means of an ice hook or other convenient tool. The reverse process restores the grate to inoperative position. Thus the formation of the grate in a plurality of independently movable sections makes for convenience and speed in moving it to and from operative position, the small sections being much easier to manipulate than would be a single grate the full size of the ice compartment.

60 It is to be noted that my grate, when in operative position, is solid and substantial, the interlocking engagement of the grate flanges 20 with the supporting flanges 21 and 22 holding the grate sections firmly in position as well as supporting their free edges, and that the shiftable hinge connections provide a simple and easily operated means for swinging the sections downwardly to inoperative position.

It is also to be noted that the grate sections, 70 when in inoperative position, do not restrict the capacity of the ice compartment for full icing, being entirely out of the way of the ice resting upon the bottom grate 12, the inner faces of said sections being flush with the inner wall 11 of the ice compartment. The only projecting members

are the flanges 17 of the hinge brackets 16, but these, because of their small size and their inclined upper edges, present no interference to the loading of the ice. Moreover, the corrugated construction of the grate sections prevents them from 5 obstructing the circulation of air in the spaces 8' and 9', even though the sections are housed within said spaces when in inoperative position.

A still further advantage in my sectional grate construction lies in the fact that it simplifies the 10 change from stage icing to full icing, or vice versa, when there is ice in the ice compartment. For example, it frequently occurs that a car which has been used with stage icing comes in from its run with some ice left in its ice compartments, 15 and must be immediately sent out again with full icing. In such case, the operator descends into the ice compartment, moves the remaining ice to one side of the auxiliary grate so that it rests upon only one or at most two sections thereof, 20 swings down the free side section to inoperative position, lowers the ice through the opening so formed in the auxiliary grate and piles it upon the bottom grate, and finally swings down the remaining section or sections, whereupon the compartment is ready to receive a full load of ice. Thus the change is made without removing the remaining ice from the compartment, as would be necessary if the auxiliary grate were in one 25 piece. 30

I claim:

1. In a refrigerator car, an ice compartment provided with spaced inner and outer walls, a portion of the inner wall being cut away to form an aperture; and an ice-supporting grate in said compartment, said grate being pivotally mounted to swing into inoperative position within said aperture, the inner surface of said grate, when in said inoperative position, forming a continuation of said inner wall. 40

2. In a refrigerator car, an ice compartment having inner and outer walls separated by an air space, an ice-supporting grate in said compartment, said grate being movable into inoperative position within said air space; and parallel stiffening corrugations in said grate, said corrugations forming channels for the free circulation of air within said air space when the grate is in inoperative position. 45

3. In a refrigerator car having an ice compartment, an ice-supporting grate within said compartment composed of a plurality of sections hinged to different walls of the compartment to swing into and out of operative position; and means for supporting the free edge of one section when in operative position from the wall opposite its hinge, the free edges of the other sections being supported by the first section. 50

4. In a refrigerator car having an ice compartment, an ice-supporting grate within said compartment; a horizontally shiftable pivotal mounting connecting one edge of said grate with one wall of said compartment whereby it may be swung into and out of operative horizontal position, a flanged bracket secured to the opposite wall of said compartment; and a flange formed upon the free edge of the grate for interlocking engagement with said bracket to support said grate in operative position, said interlocking flanges preventing horizontal movement of the grate when loaded in operative position, and said shiftable pivot permitting such horizontal movement when the grate is elevated slightly from said operative position, whereby said flanges will 65 70 75

clear each other to enable the grate to be swung downwardly to inoperative position.

5. In a refrigerator car having an ice compartment, an ice supporting grate within said compartment; a horizontally shiftable pivotal mounting for said grate comprising a pivot pin and a member provided with a substantially horizontal slot in which said pin rides, said slot having a notch in its lower side near one end engageable by said pin; and a fixed bracket for supporting the free edge of the grate opposite said pivotal mounting when said grate is in horizontal operative position, the shiftable pivot permitting the grate to be moved horizontally to enable its free edge to clear said bracket whereby said grate may be swung downwardly to its inoperative position, and the engagement of said pin with said notch impeding horizontal movement of said grate when in said inoperative position.

10. In a refrigerator car, an ice compartment having inner and outer walls separated by a space for the circulation of air, a portion of the inner wall being cut away to form an aperture; an ice-supporting grate pivotally mounted to swing from horizontal operative position to vertical inoperative position within said aperture with its face substantially flush with said inner wall to form a continuation thereof; a pivot pin for said grate, said grate being formed of sheet metal with marginal stiffening flanges along two opposite edges, one of said flanges embracing said pivot pin, and said grate being further formed with spaced parallel stiffening and draining corrugations extending at right angles to said flanges, said corrugations projecting into said air space when the grate is in vertical position and forming vertical channels between them to permit free circulation of air through said space, and said marginal stiffening flanges being of materially less depth than 30 said corrugations, whereby said intervening vertical channels are not obstructed.

7. In a refrigerator car having an ice compartment provided with inner and outer walls, respectively located in spaced vertical planes, an ice-supporting grate in the bottom portion of said compartment, and a second ice-supporting grate positioned above said bottom grate, said second grate being pivotally mounted to swing into inoperative position within the space defined by 45 said spaced vertical planes.

8. In a refrigerator car having an ice compartment, a grate within said compartment pivotally mounted to swing to and from a substantially horizontal ice-supporting position, said 50 grate comprising a plurality of complementary sections the axes of the pivots of adjacent sections being perpendicular to each other.

9. In a refrigerator car having an ice compartment provided with spaced inner and outer walls forming its ends and sides, an ice-supporting grate within said compartment, said grate comprising a plurality of sections pivotally mounted to swing into inoperative positions within the 55

spaces between said inner and outer walls, one of said sections swinging into the space of an end wall and another section swinging into the space of a side wall of said compartment.

10. In a refrigerator car having an ice compartment provided with substantially vertical walls, lining members spaced from said walls to provide air flues therebetween, a portion of one of said walls being unlined, an ice supporting grate within said compartment, said grate being movable from its ice supporting position to a substantially vertical inoperative position spaced from the unlined wall portion, and said grate forming a continuation of said lining when in said inoperative position.

11. In a refrigerator car having an ice compartment comprising inner and outer walls separated by an air space to provide an air circulating flue, said inner wall having an aperture therein, an ice supporting means in the bottom portion of the compartment, a member pivotally mounted to swing to a horizontal position to form an ice supporting means for stage icing and to swing downwardly to a vertical position within said aperture and substantially within 25 the plane of the inner wall and forming a continuation thereof so that the compartment can be used for full icing.

12. A structure as defined in claim 11 wherein the member is provided with stiffeners extending within said space and in a substantially vertical direction, when the member is in vertical position, to divide the flue into channels for air circulation between the stiffeners.

13. A structure as defined in claim 11 wherein the member is provided with stiffeners bearing against the outer wall, when the member is in vertical position, to restrict the outwardly swinging movement of the member.

14. A structure as defined in claim 11 wherein the member is pivotally mounted upon the outer wall independently of the inner wall.

15. A structure as defined in claim 11 wherein the member is provided with holes for drainage when the member is in horizontal position and 45 for movement of air into said space when the member is in vertical position.

16. A structure as defined in claim 11 wherein the member is made of a metallic plate formed with substantially parallel corrugations which 50 extend within said space in a substantially vertical direction, when the member is in vertical position, to divide the flue into channels for air circulation between the corrugations, said corrugations having holes therein for drainage, when 55 the member is in horizontal position, and for movement of air into said air space when the member is in vertical position.

17. A structure as defined in claim 11 wherein the pivotal means supports the member independently of the inner wall.

HORACE GIDDINGS.
